[57] CLAIM

The ornamental design for a carpenter's level, as shown and described.

DESCRIPTION

FIG. 1 is a top, front and left side perspective view of a carpenter's level showing our new design;
FIG. 2 is a front elevational view;
FIG. 3 is a top plan view;
FIG. 4 is a bottom plan view;
FIG. 5 is a rear elevational view;
FIG. 6 is a right side elevational view;
FIG. 7 is a left side elevational view;
FIG. 8 is a cross-sectional view of FIG. 1 taken along line 8—8;
FIG. 9 is a top, front and left side perspective view of an embodiment of our new design of FIGS. 1-8;
FIG. 10 is a front elevational view;
FIG. 11 is a top plan view;
FIG. 12 is a bottom plan view;
FIG. 13 is a rear elevational view;
FIG. 14 is a right side elevational view;
FIG. 15 is a left side elevational view; and,
FIG. 16 is a cross-sectional view of FIG. 1 taken along line 16—16 thereof.
FIGS. 1 and 9 have been drawn on an enlarged scale with respect to FIGS. 2-8 and 10-16.
